UNITED STATES PATENT OFFICE.

RUSSELL HUFF, OF DETROIT, MICHIGAN, ASSIGNOR TO PACKARD MOTOR CAR COMPANY, OF DETROIT, MICHIGAN, A CORPORATION OF MICHIGAN.

DESIGN FOR A MANIFOLD FOR INTERNAL-COMBUSTION ENGINES.

42,581.

Specification for Design.

Patented June 4, 1912.

Application filed November 27, 1911. Serial No. 662,774. Term of patent 7 years.

To all whom it may concern:

Be it known that I, RUSSELL HUFF, a citizen of the United States, residing at Detroit, in the county of Wayne and State of Michigan, have invented a new, original, and ornamental Design for a Manifold for Internal-Combustion Engines, of which the following is a specification, reference being had to the accompanying drawing, forming part thereof.

The figure is a side elevation of the manifold showing my design.

I claim:

The ornamental design for a manifold for internal combustion engines, as shown.

RUSSELL HUFF.
